CLAIM

The ornamental design for a transceiver and stand, as shown and described.

DESCRIPTION

FIG. 1 is a perspective view of a transceiver and stand showing our new design;

FIG. 2 is a front view thereof;

FIG. 3 is a rear view thereof;

FIG. 4 is a right side view thereof;

FIG. 5 is a left side view thereof; and,

FIG. 6 is a top view thereof.

The broken line showings of the ring within the claimed design and the bottom section of the stand are for illustrative purposes only and form no part of the claimed design. The unshaded bottom section of the stand and the unshown bottom of the stand form no part of the claimed design.
